(57) **CLAIM**

We claim the ornamental design for a light emitting diode lamp, as shown and described.

DESCRIPTION

FIG. 1 is a top perspective view of a light emitting diode lamp of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a top perspective view thereof shown in an environmental use.

The broken line showing of light emitting diode lamp is included for the purpose of illustrating environment and forms no part of the claimed design.
